ABSTRACT OF THE DISCLOSURE

A process for converting cyclopentadiene hydrocarbons to aromatic hydrocarbons by conducting a mixture of a diluent, such as steam, and cyclopentadiene hydrocarbons through a first reaction zone maintained at a temperature range of from about 250° to 400° C. and conducting the hot effluent from the first reaction zone through a second reaction zone maintained at about 700° to 900° C. and separating the resultant aromatic hydrocarbons from the hydrocarbon product phase.

BACKGROUND OF THE INVENTION

This invention relates to a novel method of preparing aromatic hydrocarbons, useful, for example, as motor fuel blending stock. More specifically the invention involves a method of producing aromatic hydrocarbons, principally benzene and naphthalene, directly from cyclopentadiene hydrocarbons.

It is well known that some aromatic hydrocarbons, especially benzene and naphthalene types, are useful as motor fuel blending stock. Also, it is well known that cyclopentadiene hydrocarbons are commonly produced as by-products in processes involving the carbonization of coke and the cracking of petroleum products. The cyclopentadiene hydrocarbons readily convert to their dimers and co-dimers, i.e., different cyclopentadiene hydrocarbons in polymer form, upon standing because of their reactive nature. The dimers and co-dimers are readily reconverted to their monomers upon mild heating. However, attempts to further process the cyclopentadiene hydrocarbons have, heretofore, resulted in the formation of copious amounts of coke and tars due to their highly unsaturated nature. Therefore, it has been the practice in the industry to pass streams containing cyclopentadiene hydrocarbons through a mild hydrogenation step to convert them to less reactive cyclo-olefins and cyclo-paraffins. Following such treatment the cyclo-olefins and cyclo-paraffins may be further processed to form blending stocks for motor fuels.

SUMMARY OF THE INVENTION

By utilizing the techniques of the present invention, it is now possible to convert cyclopentadiene hydrocarbons directly to highly stable aromatic hydrocarbons which make superior motor fuel blending stocks. The operation of the present process permits the separation and recovery of pure aromatic hydrocarbons by conventional separation methods.

2

It is a principal object of the present invention to produce highly stable aromatic hydrocarbons directly from cyclopentadiene hydrocarbons readily obtained as by-products from the cracking of petroleum products and from the carbonization of coke.

5 The invention, as well as additional objects and advantages thereof, will be readily apparent from a reading of the detailed description presented hereinafter.

The term "space velocity" as used herein designates grams of cyclopentadiene hydrocarbons per unit volume of reaction zone, in milliliters, per hour.

10 "Cyclopentadiene hydrocarbons" as herein employed designates monomeric cyclopentadiene and substituted cyclopentadienes, dimers and co-dimers of cyclopentadiene and substituted cyclopentadienes and mixtures thereof, wherein the substituted cyclopentadiene hydrocarbons correspond to the formula

20 wherein each R individually represents H or a hydrocarbon group derived from an alkane, olefin, diolefin, or acetylene hydrocarbon containing from 1 to 12, inclusive, carbon atoms, and where n is an integer ranging from 1 to 5.

25 In accordance with the present invention, usually a mixture of at least one cyclopentadiene hydrocarbon and a diluent is first mildly heated in a first reaction zone maintained at about 250° C. to 400° C. to convert any dimers or co-dimers to the corresponding cyclopentadiene monomers. The hot vapor effluent therefrom, containing 30 the diluent and the monomeric cyclopentadiene hydrocarbons, is conducted through a second reaction zone which is maintained at an elevated temperature of from about 700° to 900° C. whereupon the cyclopentadiene hydrocarbons are converted to highly stable aromatic hydrocarbons. The aromatic hydrocarbons are separated 35 from the product hydrocarbon phase by such standard techniques as distillation, crystallization, or absorption, and unreacted cyclopentadiene hydrocarbons are generally recycled through the process. The first low temperature reaction zone may be by-passed if monomeric cyclopentadiene hydrocarbons are available as feed stock. It 40 has been discovered in accordance with this invention that the diluent present efficiently prevents the formation of tars and carbonaceous material which have heretofore 45 been associated with high temperature treatment of cyclopentadiene hydrocarbons.

DESCRIPTION OF THE PREFERRED EMBODIMENT

50 In practice one or more cyclopentadiene hydrocarbons are passed through a reaction zone maintained at about 250° to 400° C. concurrently with a substantially equal weight of a gaseous diluent which is substantially inert to the reactants and reactant products at the reaction conditions, such as steam, at a flow rate sufficient to assure a substantially complete conversion of any dimer compounds to their corresponding monomers. To assure good 55 contact and distribution of the feed stock, the first reac-

tion zone should preferably be packed with an inert material such as Raschig rings, Berl saddles, or the like packing materials which promote reactant contact and distribution.

The hot vapor effluent from the first reaction zone is conducted through a second reaction zone heated to a temperature of from about 700° to 900° C., at a sufficient flow rate to assure a substantially complete conversion of the cyclopentadiene hydrocarbons to aromatic hydrocarbons. In the second zone the desired conversion of cyclopentadiene hydrocarbons to aromatic hydrocarbons occurs. When a source of monomeric cyclopentadiene compounds is available, they need only be conducted through the second reaction zone with the requisite quantity of diluent as set forth herein and at the designated space velocity and temperature ranges to convert them to aromatic hydrocarbons.

The effluent vapors from the second reaction zone are cooled and condensed and the aromatic hydrocarbons produced are isolated from the product hydrocarbon phase by conventional separation methods; unreacted cyclopentadiene hydrocarbons generally are recycled through the process steps.

The process as described herein is normally run at atmospheric pressure but it can be carried out at higher or lower pressures.

The reaction zone temperatures can be varied within designated ranges, as indicated. It has been observed, however, that the most efficient conversion of the dimers and co-dimers to their monomers is achieved by maintaining the first reaction zone at about 400° C. The second reaction zone ordinarily is maintained within a range of from about 700° to 900° C. The system is less efficient at temperatures lower than about 700° C. in the second reaction zone and greater proportions of cyclopentadiene hydrocarbons must be recycled through the process. Temperatures greater than about 900° C. cause degradation of the cyclopentadiene hydrocarbons and of the aromatic hydrocarbons produced. The most favorable temperature associated with the second reaction zone is about 850° C.

The flow rate, defined as a space velocity of the cyclopentadiene hydrocarbons, varies in accordance with the respective dimensions of the two reaction zones. It has been found that a space velocity of from about 0.1 to 2.0 grams cyclopentadiene hydrocarbons per milliliter reactor volume per hour is operable. A space velocity of approximately 0.6 gm./ml./hr. is preferred. Lower space velocities cause plugging of the reaction apparatus while higher velocities produce a less efficient yield rate.

The presence of a diluent is necessary to avoid carbonization and tar formation. Examples of suitable diluents are steam, nitrogen, carbon dioxide, argon, aliphatic hydrocarbons, aromatic hydrocarbons, and the like which are substantially inert to the reactants and reactant products during operation of the process. The proportion of diluent to initial cyclopentadiene hydrocarbons is expressed in the weight of diluent to the weight of feed stock. A proportion of one to one has been observed to produce the maximum economical limit but higher ratios are operable. Proportions of lower than 1:1 can be used, however, proportions lower than 0.2:1 cause excessive plugging. A proportion of from about 0.5:1, to

about 1:1 is preferred in the actual operation of the process.

1 The cyclopentadiene hydrocarbon feed stock can con-
5 sist of substantially pure monomeric cyclopentadiene
hydrocarbons or products from petroleum cracking and
from the carbonization of coke after distilling off the
heavier products may be used. For example, debutanizer
bottoms have been utilized as starting feed stocks in the
10 actual operation of the present invention. When the feed
stock consists principally of monomeric cyclopentadienes
they need only be conducted through the second reaction
zone at the conditions indicated herein.

As indicated, both cyclopentadiene and substituted cyclopentadiene hydrocarbons are operable as initial feed stocks. Dicyclopentadiene and methylcyclopentadiene have been used as feed stocks. Other substituted cyclopentadiene hydrocarbons are advantageously used, such as, for example, 2-hexyl-methylcyclopentadiene, 1-ethenyl-3-octa-dicyclopentadiene, 1-pentyl-4-octenyl-dicyclopentadiene, 1-methyl-3-propylacetylenedicyclopentadiene.

20 diene, 1-methyl-3-propylacetylenedicyclopentadiene.

Benzene, naphthalene and toluene are the principal aromatics produced in the operation of the present invention along with indene and minor amounts of other substituted aromatic hydrocarbons.

25 The method of the present invention can be run as a continuous operation with a means for recycling unreacted cyclopentadiene hydrocarbon or as a batch-type operation, and as indicated the first reaction zone is not required when the feed stock consists primarily of monomeric cyclopentadiene hydrocarbons.

The following examples further illustrate the utility and operation of the present invention. They are included herein to aid in understanding the present invention and are not meant to limit the scope of the invention to the specific examples enumerated.

Example 1

An apparatus was set up in which a vertical two-zone reactor was mounted in two electric furnaces for temperature control. The reactor consisted of a section of $\frac{3}{4}$ -inch schedule 40, type 446, stainless steel pipe. The upper zone was packed with $\frac{1}{4}$ inch Berl saddles, and maintained at about 380° C. The lower zone was the remainder of the open tube and its temperature was adjusted in a step-wise fashion from 700° to 900° C. in 50° C. steps. Dicyclopentadiene and a substantially equal weight of water were fed continuously to the upper zone of the reactor at a rate of 50.9 and 50.1 grams per hour respectively or, as expressed in space velocity, 0.582 gram dicyclopentadiene per milliliter reactor volume per hour.

Effluent vapors from the lower reaction zone were conducted to a conventional water-cooled condensing and receiving apparatus and non-condensable gases were continuously metered and then vented. Representative liquid 55 and gaseous samples were taken at each temperature level of the second reaction zone and analyzed by infrared and mass spectrographic techniques. The quantities of specific aromatics produced in both the gaseous and liquid phases were calculated from the analyses and are tabulated in following Table I. Approximately 14 to 65 pounds 60 of total aromatics per 100 pounds of dicyclopentadiene feed were made, depending on the operating temperatures employed. The major aromatics produced were the more desirable benzene and naphthalene.

TABLE I

Feed stock	Oper- ating temp., ° C.	Percent liquid recovery	Lbs. liquid phase recovered per 100 lbs. feed stock						Gas phase		Total aromatics, lbs./100 lbs. feed stock	
			Benzene	Toluene	Styrene	Inderic	Naphtha- lene	α-Methyl naphtha- lene	β-Methyl naphtha- lene	Benzene	Toluene	
Dicyclopentadiene	700	95.75	6.22				3.83	3.83				13.88
	750	83.55	6.27				13.37	12.53				32.20
	800	76.21	6.10				16.77	22.86				50.83
	850	82.58	6.61	4.13			14.04	28.90				65.17
	900	78.46	4.71	5.49			5.88	29.81				58.30

Example 2

The process described in Example 1 was repeated using methyl cyclopentadiene dimer as the feed stock. Flow rates, temperatures, space velocities, and proportions were essentially identical to those employed in Example 1. The calculated yields of aromatic hydrocarbons are presented in following Table II. Approximately 30 to 57 pounds of aromatics were produced per 100 pounds of methyl cyclopentadiene feed stock and benzene and naphthalene were the major constituents.

10

aromatic hydrocarbons and unreacted cyclopentadiene hydrocarbons.

3. The process as defined in claim 1 and including the additional step of recycling unreacted cyclopentadiene hydrocarbons through said sequential reaction zones at said flow rate and temperature ranges.

4. The process as defined in claim 1 wherein the cyclopentadiene hydrocarbon is a member of the group consisting of monomeric cyclopentadiene and substituted cyclopentadienes; dimers and co-dimers of said cyclopentadienes.

TABLE II

Feed stock	Operating temp., °C.	Percent liquid recovery	Lbs. liquid phase recovered per 100 lbs. feed stock						Gas phase		Total aromatic, lbs./100 lbs. feed stock	
			Benzene	Toluene	Styrene	Indene	Naphthalene	α-Methyl naphthalene	β-Methyl naphthalene	Benzene	Toluene	
Methyl cyclopentadiene dimer	700	88.96	20.02	5.34	-----	1.78	2.67	-----	4.02	0.31	0.03	30.15
	750	80.35	20.49	7.63	-----	4.42	9.64	1.21	1.70	0.01	0.01	49.12
	800	78.82	20.49	6.70	-----	5.12	14.58	1.18	4.73	2.94	0.02	55.76
	850	78.22	20.34	5.87	-----	4.30	16.04	1.17	5.08	4.52	0.08	57.40
	900	71.34	17.12	3.92	-----	2.50	13.91	0.71	3.92	9.14	0.22	50.44

Example 3

A duplicate of Example 1 was run using cyclopentane as the feed stock. Conditions and procedures were essentially the same as in Example 1. The aromatic yields are listed in Table III. Approximately 1/3 the yield of the process of Example 1 was realized and then only at high temperature levels.

30

tadiene and substituted cyclopentadienes and mixtures thereof, and where said substituted cyclopentadiene hydrocarbons correspond to the formula

TABLE III

Feed stock	Operating temp., °C.	Percent liquid recovery	Lbs. liquid phase recovered per 100 lbs. feed stock						Gas phase		Total aromatic, lbs./100 lbs. feed stock	
			Benzene	Toluene	Styrene	Indene	Naphthalene	α-Methyl naphthalene	β-Methyl naphthalene	Benzene	Toluene

In accordance with the process as heretofore described, by-products from petroleum cracking processes, namely cyclopentadiene hydrocarbons, can readily be converted to highly desirable aromatic hydrocarbons useful, for example, as motor fuel blending stocks. In accordance with the actual operation of the present invention the by-products can be converted more readily and more economically than heretofore possible.

Various modifications of the invention can be made without departing from the spirit or scope thereof, for it is understood that we limit ourselves only as defined in the appended claims.

We claim:

1. A process for converting cyclopentadiene hydrocarbons to aromatic hydrocarbons comprising:
  - sequentially conducting a mixture of at least one cyclopentadiene hydrocarbon and a gaseous diluent which is substantially inert to the reactants and reactant products at the reaction conditions through a first reaction zone maintained at a temperature within the range of about 250° C. to about 400° C. at a flow rate sufficient to assure a substantially complete conversion of dimers and co-dimers of said cyclopentadiene hydrocarbons to the corresponding monomers; and
  - conducting the effluent from the first reaction zone through a second reaction zone maintained at a temperature within the range of about 700° C. to about 900° C. at a flow rate sufficient to assure a conversion of the cyclopentadiene hydrocarbons to aromatic hydrocarbons.
2. The process as defined in claim 1 and including the additional step of condensing the effluent gases evolved from the second reaction zone and separating therefrom

wherein each R individually represents H or a hydrocarbon group derived from an alkane, olefin, diolefin and acetylene hydrocarbon containing from 1 to 12, inclusive, carbon atoms, and where n is an integer ranging from 1 to 5.

5. The process as defined in claim 1 wherein the proportion of diluent to cyclopentadiene hydrocarbons is within the range of from about 0.2:1 to about 1:1 by weight.

6. The process as defined in claim 1 wherein the flow rate of said mixture through said reaction zones is maintained within the range of about 0.1 to about 2.0 grams of cyclopentadiene hydrocarbon per milliliter of reaction zone per hour.

7. The process as defined in claim 1 wherein the diluent is steam.

8. A process for converting monomeric cyclopentadiene hydrocarbons to aromatic hydrocarbons comprising:

- conducting a mixture of at least one monomeric cyclopentadiene hydrocarbon and a gaseous diluent which is substantially inert to the reactants and reactant products at the reaction conditions through a reaction zone maintained at a temperature within the range of about 700° C. to about 900° C. at a flow rate sufficient to assure a conversion of the cyclopentadiene hydrocarbons to aromatic hydrocarbons.

9. The process as defined in claim 8 and including the additional step of condensing the effluent gases evolved from said reaction zone and separating therefrom aromatic hydrocarbons and unreacted cyclopentadiene hydrocarbons.

10. The process as defined in claim 8 and including the additional step of recycling unreacted cyclopentadiene

70

75

hydrocarbons through said reaction zone at said flow rate and temperature ranges.

11. The process as defined in claim 8, wherein the monomeric cyclopentadiene hydrocarbon is a member of the group consisting of cyclopentadiene, substituted cyclopentadiene and mixtures thereof and where said substituted cyclopentadiene hydrocarbons correspond to the formula

wherein each R individually represents H or a hydrocarbon group derived from an alkane, olefin, diolefin and acetylene hydrocarbon containing from 1 to 12, inclusive, carbon atoms, and where n is an integer ranging from 1 to 5.

12. The process as defined in claim 8 wherein the pro-

portion of the diluent to the cyclopentadiene hydrocarbon is within the range of from about 0.2:1 to about 1:1 by weight.

13. The process as defined in claim 8 wherein the flow rate of said mixture through said reaction zones is maintained within the range of about 0.1 to about 2.0 grams of cyclopentadiene hydrocarbon per milliliter of reaction zone per hour.

14. The process as defined in claim 8 wherein the diluent is steam.
